UNITED STATES PATENT OFFICE

CHARLES DONLEY, OF LEBANON, PENNSYLVANIA, ASSIGNOR TO WROUGHT IRON COMPANY OF AMERICA, OF LEBANON, PENNSYLVANIA, A CORPORATION OF PENNSYLVANIA

TENSIONING MEANS FOR FEED ROLLS AND THE LIKE

Application filed July 24, 1931. Serial No. 553,018.

This invention relates to tensioning means for feed rolls and the like.

An important object of the invention is the provision in a structure of this character of an arrangement such that the tension of the tensioning spring may be adjusted as desired.

A further object of the invention is the provision of a construction of this character wherein the tappet element or element projected by the spring for operative engagement with the associated feed roll may be very readily adjusted without, except under extraordinary circumstances, being subjected to the pressure of the tensioning spring.

15 A still further object of the invention is the provision of a construction of this character such that the tappet is securely locked in its adjusted position and at the same time may be very readily released for adjustment without tearing down the mounting.

These and other objects I attain by the construction shown in the accompanying drawing wherein, for the purpose of illustration, I have shown a preferred embodiment of my invention and wherein:

20 Fig. 1 is a detail sectional view through a feed roll mounting embodying a tensioning means constructed in accordance with my invention;

Fig. 2 is an elevation of the tensioning apparatus detached;

Fig. 3 is an enlarged sectional view through the tensioning means detached; and

35 Fig. 4 is a section on line 4—4 of Fig. 3.

Referring now more particularly to the drawing, the numeral 10 generally designates a machine frame mounting bearings 11 for upper and lower feed rolls 12 and 13. Of such rolls one, usually the lower, is driven in any suitable manner, being at present shown as provided with a gear for engagement with the drive while the upper is mounted so that it may have a yielding movement to grasp a bar B or other article passing therebetween

40 and grip the same with sufficient tension to cause longitudinal movement thereof. The structure just recited is common in practically all feed roll mountings and in analogous mountings such as sheet straightening rolls and the like.

Associated with the upper feed roll is a suitable tensioning means 14, this means in accordance with my invention comprising a body element 15 at present shown as adapted to be bolted or otherwise rigidly secured to the machine frame 10 and having formed therein a bore 16 the lower end of which is reduced as indicated at 17 and the upper end of which is interiorly threaded as indicated at 18. The smaller bore 17 aligns with a bore 19 formed in the frame 10 for a purpose hereinafter to appear. The body portion 15 may, if so desired, be an integral portion of frame 10. Seated in the lower end of the enlarged portion of the bore of body 15 is a nut 20, said nut having splined engagement with the walls of the bore so that it may move vertically, but may not rotate, as indicated at 21, and more clearly shown in Fig. 4. Threaded in the nut is a tappet 22 the lower end portion of which is adapted to extend through the reduced portion 17 of the bore 16 and through the opening 19 of the frame which serves as a guide therefor. With the exception of its head and lower extremity 23, the tappet is threaded as indicated at 24 and surrounding the tappet is a sleeve 25 of a length sufficient to project well above the upper end of bore 16, for a purpose presently to appear.

Within the bore 16 is a tension spring 26, the lower end of which seats upon nut 20 and the upper end of which is abutted by a spring tensioned adjusting nut 27 engaging the threads 18 at the upper end of the bore. The upper end of sleeve 25 is preferably 80 thickened so as to afford a solid seat for a locking nut 28 engaged with the tappet 22. It will be obvious that by loosening nut 28 the tappet is freed so that it may be rotated in nut 20 and the extent of its projection through the lower end of the body 15 thus determined. When the proper adjustment has been made, the nut 28 may be forced home against the upper end of the sleeve and will, through its combination with the sleeve, operate as a lock nut with the nut 20 and so hold the tappet against release under the vibration to which all parts of such machines are continually subjected. Since the lower end of tappet 22 has operative engage- 90

ment with the upper or movable feed roll 13 through its bearing 11 and an abutment plate 29, it will be obvious that this tappet constitutes a means for determining the tension applied to the roll which is operable independently of the tension adjusting nut 27. Tappet 22 will of course yield under heavy strains permitting the feed roll to shift.

Attention is directed to the fact that the use of the sleeve, which constitutes in effect an extension of nut 28, permits adjustments to be made at any time without the necessity of tearing down the apparatus and, furthermore, permits of the provision of a relatively wide adjusting range in nut 27.

Since the construction employed is capable of a certain range of change and modification without in any manner departing from the spirit of my invention, I do not wish to be understood as limiting myself thereto except as hereinafter claimed.

I claim:

1. Tensioning means for movable feed rolls comprising a tappet operatively engaging the roll, a member fixed against rotation about the tappet while capable of movement in the direction of the axis of the tappet and through which the tappet is adjustably directed, a spring surrounding the tappet and for one end of which the member forms an abutment, a stationary abutment for the opposite end of the spring through which the tappet passes and means locking the tappet in adjusted positions disposed at the opposite face of the stationary abutment from said member.

2. Tensioning apparatus for movable feed rolls comprising a tappet operatively engaging the roll, a housing having a bore through which the tappet passes, a spring within the bore and operatively engaging the housing at one end, a nut adjustable longitudinally to the bore by rotation of the tappet mounted on said tappet and with which the opposite end of said spring engages, and means exterior to the housing locking said tappet and nut against relative rotation.

3. Tensioning apparatus for movable feed rolls comprising a tappet operatively engaging the roll, a housing having a bore through which the tappet passes, a spring within the bore and operatively engaging the housing at one end, a nut adjustable longitudinally to the bore by rotation of the tappet mounted on said tappet and with which the opposite end of said spring engages, means exterior to the housing locking said tappet and nut against relative rotation comprising a sleeve surrounding said tappet and abutting the nut, said sleeve projecting from the housing and a second nut upon the tappet engaging the projecting end of the sleeve.

4. Tensioning apparatus for movable feed rolls comprising a housing having a bore radial to the roll, a nut within the housing

and held against rotation with relation thereto but movable longitudinally in said bore, a tappet threaded through the nut and engaging the feed roll, a spring within the bore and abutting the nut, an adjustable nut disposed in said bore and engaged with the wall thereof through which the tappet passes and against which the spring abuts, a nut upon the tappet exteriorly to the housing, and means forming an extension for the last-named nut engaging the first-named nut.

5. Tensioning apparatus for movable feed rolls comprising a housing having a bore radial to the roll, a nut within the housing and held against rotation with relation thereto but movable longitudinally in said bore, a tappet threaded through the nut and engaging the feed roll, a spring within the bore and abutting the nut, an adjustable nut disposed in said bore and engaged with the wall thereof through which the tappet passes and against which the spring abuts, a nut upon the tappet exteriorly to the housing, and a sleeve surrounding the tappet between the first and last-named nuts.
